UNITED STATES PATENT OFFICE

FRANKLIN E. EVERSON, OF NEW YORK, N. Y.

DISPLAY BASKET

Application filed August 27, 1931. Serial No. 559,793.

This invention relates to display baskets, and more particularly to a collapsible display basket having improved means of construction and for holding the same in assembled relation.

Another object of the invention is the provision of a display basket which may be formed from a single piece of cardboard or the like, and which has improved means for holding the basket in upright condition thereby preventing overturning of the basket and spilling of the articles on display therein. Still another object resides in the provision of a bottom with side portions overlapping the side walls of the basket and operating to throw the weight of the article placed therein upon the sides of the basket instead of upon the bottom.

With these and other objects in view the invention resides in the novel features of construction and arrangement of parts which will be more fully described and claimed hereinafter. In the accompanying drawings illustrating the invention

25 Figure 1 is a perspective view of the basket in assembled relation;

Fig. 2 is a cross sectional view on line 2—2 of Fig. 1;

30 Fig. 3 is a bottom plan view of the basket; Fig. 4 is a plan view of the blank from which the basket is formed.

For manufacturing purposes the basket is preferably formed from a single piece of cardboard or other suitable stiff material 35 which may be cut or stamped by a single operation in the form of a blank as shown in Fig. 4. This blank is provided with broken lines indicating the lines on which the blank is folded to form the basket.

40 The basket, indicated generally by the numeral 10, is composed of a rear wall 11, side walls 12 and 13, a front wall 14 and a bottom wall 15. The rear wall 11 extends above the top edges of the said side and front

45 walls forming a rectangular panel which may be used as a means for grasping the basket for lifting the same, and which may also be used as a display panel on which printed matter may be arranged indicative of the articles displayed in the basket. In making

the blank shown in Fig. 4 the bottom edge 16 of the rear wall 11, and the bottom edges 17, 18, and 19 of the walls 12, 14, and 13 respectively, are cut on a line with each other parallel to the straight line 20 forming the top edges 21, 22, and 23 of the said walls respectively.

55 Between adjacent side walls at the side edges thereof oppositely shaped triangular gussets 24 and 25 are provided which are folded upon each other to form the triangular extended corner supporting members 26. These gussets are formed by folding the blank on the broken lines 27 perpendicular to the straight line 20 and on the diagonal lines 28 and 29 which lines extend from a point where the lines 27 intersect with the line 20 to the bottom edges 16, 17, 18, and 19 of the said walls respectively. The blank is folded inwardly on the lines 27 and outwardly, that is in an opposite direction on the lines 28 and 29, adjacent gussets being folded on each other, the lines 27 becoming the outer folded edges 30 of the triangular extensions 26 and the fold lines 28 and 29 becoming the interior edges 31 of the basket.

70 The gussets are secured together by any preferred means, as for instance, by staples 32 clinching the folds together adjacent the fold lines 28 and 29. The gussets 33 and 34 at the ends of the blank correspond in form to the gussets 24 and 25 respectively and by securing these gussets together by the said staples 32 as hereinbefore described the blank is connected in basket formation with the said side walls flaring outwardly from the bottom to the top edges thereof. Each of the said gussets has its bottom edge 35 cut on an angle to the bottom edges of adjacent side walls as shown in Fig. 4 so that when the basket is assembled the bottom edges of the triangular extensions 26 will be in a common plane with the bottom edges of the walls of the basket.

80 85 90 95 100 The bottom 15 is provided with rectangular extensions 36 which are bent upwardly along the fold lines 37 at an angle to the said bottom to overlie the said walls 11, 12, and 13, when the bottom is in operative position. These extensions operate to hold the

bottom in place and the side walls in extended relation. The said bottom is connected to the side wall 14 along the fold line 18 which line forms the bottom edge of the 5 said side wall.

While the preferred embodiment of the invention has been shown and described, it is to be understood that various changes and modifications may be made in the construction of the basket without departing from the spirit and scope of the invention.

I claim:

1. A display basket comprising a back, front and side walls, said walls flaring outwardly from the bottom to the top thereof, a folded extension projecting outwardly at each corner of the basket operating to hold the basket upright, and a bottom connected to one of said walls, said bottom being provided with outwardly extended sections adapted to overlie a portion of the remaining walls of the basket on the inside thereof and operating to hold the bottom in position and the walls of the basket extended.

25 2. A display basket comprising a back, front and side walls, a folded extension projecting outwardly at each corner of the basket operating to hold the basket upright and a bottom connected to one of said walls, 30 said bottom being provided with outwardly extended sections adapted to overlie a portion of the remaining walls of the basket on the inside thereof and operating to hold the bottom in position and the walls of the basket 35 extended.

3. A display basket comprising a back, front and side walls, an extension projecting outwardly at each corner of the basket operating to hold the basket upright, and a 40 bottom connected to one of said walls, said bottom being provided with outwardly extended sections adapted to overlie a portion of the remaining walls of the basket on the inside thereof and operating to hold the 45 bottom in position and the walls of the basket extended.

4. A display basket comprising a back, front and side walls, a folded extension at the corners of the basket integrally connected 50 to the walls of the basket and projecting outwardly to hold the basket upright, and a bottom connected to one of said walls, said bottom being provided with outwardly extended rectangular sections adapted to overlie a portion of the remaining walls of the basket on the inside thereof and operating 55 to hold the bottom in position and the walls of the basket extended.

60 5. A display basket comprising a plurality of side walls, an extension projecting outwardly at each corner of the basket operating to hold the basket upright, and a bottom connected to one of said walls, said bottom being provided with outwardly extended sections 65 adapted to overlie a portion of the remaining

walls of the basket on the inside thereof and operating to hold the bottom in position and the walls of the basket extended.

6. In a display basket, a plurality of side walls flaring outwardly from the bottom to the top thereof, and extensions projecting outwardly at the juncture of adjacent side walls operating to hold the basket upright, said extensions being formed of two plies and secured together to hold the sides of the basket 75 in operative positions.

7. In a display device, a plurality of side walls and extensions projecting outwardly at the juncture of adjacent side walls operating to hold the device upright, said extensions being formed of two plies and secured together to hold the sides of the device in operative positions.

FRANKLIN E. EVERSON.
